UNITED STATES PATENT OFFICE.

HERMANN WITTEK, OF ITZEHOE-SUDE, HOLSTEIN, GERMANY, ASSIGNOR TO PAULINE STOCK, OF ELKHART, INDIANA.

EXTENSION TABLE.

Application filed August 30, 1926. Serial No. 132,466.

My invention relates to extension tables of the type in which the extension top is carried with the table for movement into and out of extended position, and relates to a simple, effective, easily applied and economically manufactured mechanism for supporting the extension top for movement into and out of extended position.

The invention will be more fully understood by reference to the accompanying drawing forming a part hereof in which—

Figure 1 is a bottom plan view of an extension table embodying my invention;

Figure 2 is an enlarged section on the line 2—2 of Figure 1;

Figure 3 is a central vertical longitudinal section of the table with the extension parts in extended positions;

Figure 4 is an enlarged transverse section taken on the line 4—4 of Figure 3;

Figure 5 is a partial section similar to Figure 4 showing the parts in different positions.

Like characters of reference indicate like parts in the several views.

Referring to the drawing 1 designates a table frame of usual rectangular marginal form. Secured at the top of this frame and extending across the same at the center thereof is a support piece 2, and a main table top 3 is supported at its center on this support piece 2, this table top being secured with the support piece 2 against horizontal movement by a piece 4 secured on the under side of the table top and engaged in a corresponding aperture of the support piece to permit vertical movement of the table top.

Extension table tops 5 are provided which are adapted to lie between the frame 1 and the top 3 on respective sides of the support piece 2 when in folded or contracted positions as shown in Figures 1 and 2. Each of these extension tops 5 is carried for movement into and out of extended position in the following manner. A pair of parallel support members 6 of right angle section are secured at the underside of a respective extension top 5 with legs of the angle section thereof disposed in vertical planes, and these supports extend outwardly beyond the inner side of this extension top. Bearing rollers 7, revolvably mounted on suitable brackets 8 secured on the inside of a respective side of the frame 1, comprise outer bearings for

the supports 6 and engage the lower edges of the vertical legs of the supports for supporting the same for longitudinal movement. Inner bearings 9 are secured on the under side of the support piece 2 and are provided with bearing openings 10 embracing the vertical legs of the support members 6 for longitudinal movement of the support members. The support members 6 have, at their extending ends, the lower portions of the vertical legs thereof turned transversely to provide stops 11 engageable with the bearings 9 to limit extending movement of the support members, see Figures 3 and 4, and the lower portions of the bearing openings 10 are enlarged transversely, as designated at 12, to permit passage of the stops 11 therethrough in abnormal positions of the extending ends of said support members 6 with respect to the inner bearings 9. See Figure 5.

The vertical legs of the support members 6 underlying the extension top 5 are tapered upwardly toward these ends, as designated at 13, and the extending portions of the support members 6 extend downwardly at an acute angle to the plane of the extension top, as designated at 14, in order to elevate the extension top 5 to the normal plane of the main top 3 when the extension top 5 is in extended position, as shown in Figure 3, and to position the extension top 5 below the normal plane of the main top 3 when the extension top 5 is in folded or contracted position as shown in Figure 2.

In extending the extension top 5 it is pulled outwardly until the stops 11 engage the bearings 9 and as it elevates in its outward movement the main top 3 is lifted until the extension top 5 clears the same when the main top falls back into its normal plane. In moving the extension top 5 into folded or contracted position the main top 3 is first lifted to clear the extension top and the extension top is then moved inwardly.

If it is desired to remove the extension top 5 from the table it is pulled outwardly and manipulated in an obvious manner to aline the stops 11 with the enlarged portions 12 of the bearing openings 10 after which the outward movement of the extension top 5 is continued for the removal. Re-mounting of the extension top 5 is accomplished in an obviously similar manner.

While I have herein shown and particu-

larly described the preferred embodiment of my invention I do not wish to be limited to the precise details of construction shown as changes may readily be made without departing from the spirit of my invention, but having thus described my invention I claim as new and desire to secure by Letters Patent the following claims:—

1. In an extension table the combination 10 with a table frame and an extension top, of parallel supports of right angle section secured on the underside of the top with legs of the angle sections thereof disposed in vertical planes, and extending outwardly 15 beyond the inner side of the top and having at their extending ends portions of the vertical legs thereof turned transversely to provide stops, and bearings on said frame and carrying said supports for longitudinal 20 movement with respect thereto including inner bearings having bearing openings embracing the vertical legs of said supports and having portions of said openings enlarged transversely to permit the passage 25 of said stops therethrough in an abnormal position of said extending ends of said supports with respect thereto.
2. In an extension table the combination 30 with a table frame and an extension top, of parallel supports of right angle section secured on the underside of the top with legs of the angle sections thereof disposed in vertical planes, and extending outwardly beyond the inner side of the top and having 35 at their extending ends the lower portions of the vertical legs thereof turned trans-

versely to provide stops, and bearings on said frame and carrying said supports for longitudinal movement with respect thereto including inner bearings having bearing 40 openings embracing the vertical legs of said supports and having the lower portions of said openings enlarged transversely to permit the passage of said stops therethrough.

3. In an extension table the combination 45 with a table frame and an extension top, of parallel supports of right angle section secured on the underside of the top with legs of the angle sections thereof disposed in vertical planes, and extending outwardly beyond the inner side of the top and having at their extending ends portions of the vertical legs thereof turned transversely to provide stops, outer bearing rollers on said frame 50 engaging the lower edges of said vertical legs for supporting the same for longitudinal movement, inner bearings on said frame having bearing openings embracing the vertical legs of said supports and having the lower portions of said openings enlarged 55 transversely to permit the passage of said stops therethrough, said vertical legs having the lower edges thereof of the end portions thereof underlying said top tapered 60 upwardly toward these ends and said extending portions of said supports extending downwardly at an acute angle to the plane of said top.

In witness whereof I affix my signature this third day of August, 1926.

HERMANN WITTEK.
